DESIGN FOR A MATERNITY GIRDLE

Gaylord A. Barcley, South Orange, N. J.

Application November 8, 1940, Serial No. 96,438

Term of patent 14 years

To all whom it may concern:

Be it known that I, Gaylord A. Barcley, a citizen of the United States and a resident of South Orange, in the county of Essex and State of New Jersey, have invented a new, original, and ornamental Design for a Maternity Girdle, of which the following is a specification, reference being had to the accompanying drawings, forming part thereof.

I claim:

The ornamental design for a maternity girdle, as shown.

GAYLORD A. BARCLEY.
